DESIGN FOR A FONT OF NUMERALS

Lucian Bernhard, New York, N. Y., assignor to Keuffel & Esser Company, Hoboken, N. J., a corporation of New Jersey

Application April 26, 1945, Serial No. 119,229

Term of patent 14 years

(Cl. D64—12)

To all whom it may concern:

Be it known that I, Lucian Bernhard, a citizen of the United States, and residing in the city of New York, county of New York, and State of New York, have invented a new, original, and ornamental Design for a Font of Numerals, of which the following is a specification, reference being had to the accompanying drawing, forming a part thereof.

The drawing shows a font of numerals embodying
my new design.

I claim:

The ornamental design for a font of numerals,
as shown.

LUCIAN BERNHARD.
